UNITED STATES PATENT OFFICE.

WALTER E. MOWREY, OF ARNOLD, NEBRASKA.

PHOTOGRAPHIC-PLATE HOLDER.

1,279,407.

Specification of Letters Patent. Patented Sept. 17, 1918.

Application filed March 13, 1918. Serial No. 222,145.

To all whom it may concern:

Be it known that I, WALTER E. MOWREY, a citizen of the United States, residing at Arnold, in the county of Custer and State 5 of Nebraska, have invented certain new and useful Improvements in Photographic-Plate Holders, of which the following is a specification.

The purpose of this invention is the provision of a holder for photographic cameras 10 which is adapted to receive plates of different sizes and which operates effectively with the different sized plates so as to secure them in the required position against possible displacement.

The invention primarily aims to provide means in the nature of an attachment which may be readily adapted to plate holders in use or on the market whereby their range of 20 usefulness is materially increased.

The invention provides adjustable plate holding means which may be cheaply manufactured and which are light and compact so as to be readily adapted to plate holders 25 of ordinary structure.

The drawing illustrates a preferred embodiment of the invention, however, it is to be understood that in adapting the same to meet different conditions, various changes in 30 the form, proportion, and minor details of construction may be resorted to without departing from the nature of the invention as claimed hereinafter.

In the drawings:

Fig. 1 is a plan view of a photographic plate holder of ordinary formation provided with adjustable plate holding means embodying the invention, the obverse slide being drawn outward and having the intermediate portion broken away.

Fig. 2 is a transverse section on the line 2—2 of Fig. 1 looking in the direction of the arrows.

Fig. 3 is a perspective view of one member 45 of the adjustable plate holding means.

Fig. 4 is a perspective view of the complementary member of the adjustable plate holding means.

Corresponding and like parts are referred 50 to in the following description and indicated in the several views of the drawings by like reference characters.

The plate holder comprises a frame 1, slides 2, and an intermediate partition 3, 55 these parts being of well known construction and arrangement in camera plate holders.

The plate is indicated at 4, and may be of any size within the capacity of the holder, it being understood that within certain limits, plates of different sizes are adapted to be 60 used in connection with the holder, the present invention relating to the means whereby such plate is made secure when in position.

The adjustable plate holding means comprise complementary members A and B. Each of these members is preferably formed of sheet metal of proper size. The member A comprises a shank 5 and a head 6. Intercommunicating slots 7 and 8 are formed in 70 the head 6 and are disposed relatively at a right angle to each other. A slot 7 is open at one end and is disposed transversely of the member a short distance from the outer edge of the head 6. The slot 8 is closed and 75 extends lengthwise of the member and is disposed near a longitudinal edge thereof. The slots 7 and 8 are adapted to receive a fastening 9 which secures the member A in the required adjusted position. The longitudinal edge portion of the head 6 adjacent 80 the slot 8 is offset, as indicated at 10 to provide a lip which in practice engages over an edge portion of the plate 4 and retains it in the required position. One end of the lip 85 extension 10 is bent downwardly, as indicated at 11 to engage an edge of the plate 4 and prevent displacement of the plate after the parts have been properly assembled.

The complementary member B of the plate 90 holding attachment comprises a head 12 and a shank 13, the latter being designed to overlap the shank 5 of the member A and having its edge portions folded, as indicated at 14 to provide guide-ways which embrace 95 opposite edge portions of the shank 5 and thereby retain the parts in proper position. The head 12 is formed with slots 15 and 16 which correspond with the slots 7 and 8 of the member A and have a like arrangement 100 and are designed to receive a fastening 17 which performs the same office as the fastening 9. A lip extension 18 is offset from the longitudinal edge portion of the head 12 adjacent the longitudinal slot 16 and is provided at its outer end with a depending portion 19 for a purpose similar to the part 11 of the member A. The members A and B being formed of sheet metal are light, capable of being cheaply constructed and 110 occupy a minimum amount of space, thereby adapting an attachment after plate holders

extant. The fastenings 9 and 17 consist of screws and may be threaded into the partition 3 of a plate disposed upon the reverse side of such partition.

- 5 The full and dotted lines in Fig. 1 indicate two positions of the adjustable plate holding means. In the position indicated by the full lines the fastenings 9 and 17 are disposed in the longitudinal slots 8 and 16, 10 but in the dotted line position shown in Fig. 1, the fastenings are disposed in the transverse slots 7 and 15 of the members A and B. It is contemplated to provide holding means for two sizes of plates and to supply 15 different sizes of holding members for every two remaining sizes of plates within the capacity of the holder. This will necessitate differently positioning the fastenings 9 and 17, hence the partition 3 will have openings 20 at different points for such fastenings, but the openings not required for immediate use will be covered by suitable material such as adhesive plaster or other material pasted to the partition and covering the openings 25 therein.

As indicated in Fig. 1, the plate holding means are disposed at one end of the holder, and when the plate 4 is in position, it is confined at one end by means of the lip extensions 10 and 18 and the bent portions 11 and 19 of such extensions. When the fastenings 9 and 17 are loosened the members A and B may be readily adjusted to the next size and when positioned are made secure by 35 tightening the fastenings 9 and 17, such fastenings being loosened and tightened by means of a suitable tool.

What I claim is:

1. Adjustable plate holding means for a 40 photographic camera plate holder, the same comprising complemental members disposed on the partition of the plate holder, and each

member being provided with intercommunicating right-angularly disposed slots and provided with plate engaging extensions, 45 and fastening means coöperating with the slots of the members to secure them to said partition in the required adjusted position.

2. In combination with a photographic plate holder embodying a frame and a partition, complemental members each comprising a shank and a head, the shanks of the members having sliding engagement and the heads being provided with right-angularly disposed slots, and fastenings passing 55 through the slots of the heads to secure the members of the partition in the required adjusted position.

3. In combination with a photographic plate holder, complemental members, each of 60 such members having an offset plate engaging extension and having the outer ends of such extension bent to engage the outer edges of the plate, and fastening means for securing the members of the holder in the required 65 adjusted position.

4. An adjustable plate holding means for photographic plate holders, the same comprising complemental members each of such members consisting of a shank and a head, 70 the latter having an edge portion offset to provide a plate engaging extension and such plate engaging extension having its outer end bent, the shanks of the members having sliding engagement and the heads of the 75 members being provided with right-angularly disposed inter-communicating slots.

In testimony whereof I affix my signature in presence of two witnesses.

WALTER E. MOWREY.
